UNITED STATES PATENT OFFICE.

FRANK FIEBEGER, OF AKRON, OHIO.

GRATE FOR FURNACES.

SPECIFICATION forming part of Letters Patent No. 710,570, dated October 7, 1902.

Application filed December 11, 1901. Serial No. 85,419. (No model.)

To all whom it may concern:

Be it known that I, FRANK FIEBEGE, a citizen of the United States, residing at Akron, in the county of Summit and State of Ohio, have invented a certain new and useful Improvement in Grates for Furnaces, of which the following is a specification.

My invention has relation to improvements in that class of grates for furnaces and like heating instrumentalities of a type known as the "rocking-bar" grate; and the object of my invention is to produce a new and improved grate of the class named in which the rocking grate-bars shall be arranged in pairs, with gearing connected with the several pairs by which a single pair may be simultaneously rocked without disturbing the adjacent pair, in which the bar-frame may be readily dropped at the front to permit the removal of clinkers or the removal of a worn-out bar and the substitution of a new one, and for this latter purpose to provide a separable cross journal-bearing for the axles of the bars, and as a final purpose to enable the grate-frame to be readily removed and replaced without taking the furnace to pieces.

To the aforesaid objects my invention consists in the peculiar and novel construction, arrangement, and combination of parts hereinafter described and then specifically pointed out in the claim, reference being had to the accompanying drawings, which form a part of this specification.

In the accompanying drawings, in which similar reference-numerals indicate like parts in the different figures, Figure 1 is a plan of an ash-pit of a furnace in section on the plane of grate and provided with my improved grate; Fig. 2, a side elevation of the same looking from the left of Fig. 1, with the ash-pit in fore-and-aft vertical section and the grate dropped at the front to permit the removal of clinkers, or as also illustrating its first position in inserting the grate into the furnace or removing it therefrom; and Fig. 3, the front bar of the grate-frame, illustrating how it is separable to permit the insertion or removal of grate-bars.

Referring to the figures, 1 is the ash-pit wall, with a door-easing 2. On the opposite inner faces of the ash-pit, at the back, are

trunnion-supports 3, the one in Fig. 2 being shown in section at the inner face of the ash-pit, which consist of brackets that may be attached to or integral with the ash-pit and have their rear ends curved upward to prevent the trunnion passing over and their front ends similarly curved upward, but in a less degree. On the opposite inner faces of the ash-pit, at the front, are two front arm-supports 4, similarly constructed and having semicircular notches in the top.

The grate-frame 5 has trunnions 6 at the sides near the back to rest in the supports 3 and at the sides near the front arms 7 to rest in the supports 4, the parts being so constructed that the arms 7 will rest in the supports 4 when the trunnions 6 are at the back of the supports 3, but will pass over the fronts of the supports 3, when those trunnions are drawn to the front of the supports 3.

The front bar of the frame 5 consists of two parts, as shown in Fig. 3, the lower half being reduced from above to form a seat for the upper half, and has at one end a sloping mortise to receive a tenon 8 and at about its center and near the other end mortised to receive tenons 9 10 of the upper half, which latter tenons have holes for locking-pins.

The frame 5 is circular at the back, the circle being completed by a curve 11.

The grate-bars are substantially similar in construction, the inner ones 12 being alike, and each embodies a central shaft with integral projecting fingers from each side, the fingers of both bars being in alinement with each other and of such length as to nearly meet. The outer bars 13 are similarly constructed; but the number of fingers is necessarily reduced to adapt them to the smaller spaces in which they rock and alternate with the fingers of the bars 12. The back ends of these bars are fitted to turn in openings in the back of the frame 5, (indicated by dotted lines in Fig. 1,) and their front ends are journaled in the lower half of the frame-front and retained by the upper half. The inner bars 12 extend through the frame-front and are provided with sockets 14 to receive a tool by which they may be rocked. The inner part of the circle of the frame has integral projections to partially fill the spaces not filled by the teeth of

the bars 12. On each inner bar 12 and each outer bar 13 are mounted, respectively, small gears or pinions 15 16, that mesh together, one pair being set farther inward from the 5 front bar of the frame 5 than the other, by which arrangement an inner bar and its adjacent outer bar can be simultaneously rocked in opposite directions without disturbing the other.

10 The grate is prepared for use by mounting the bars in their journal-bearings, just described, and inserted in the furnace by raising the back end of the frame until the trunnions 6 will pass over the front ends of the 15 supports 3, then pushing it back until the trunnions rest in these supports, then raising the front ends of the frame until the arms 7 are high enough to pass over the supports 4, and then pushing the frame back until the 20 arms rest in these supports.

The front of the frame and grate is lowered by drawing the frame forward enough to permit the arms 7 to pass down in front of the supports 4.

Any bar may be removed by releasing the 25 upper half of the front bar.

Having thus described my invention, what I claim, and desire to secure by Letters Patent, is—

The combination with a grate-frame having 30 grate-bars mounted therein and having oppositely-disposed trunnions extending from its sides near its back, and arms extending from its sides near its front, of an inclosing case, as an ash-pit, having elongated supports with upwardly-turned ends for said trunnions to permit of their forward-and-backward movement therein, and supports to receive and fit said arms and hold them against such movement, substantially as shown and 35 described.

In testimony that I claim the above I hereunto set my hand in the presence of two subscribing witnesses.

FRANK FIEBEGER.

In presence of—

C. E. HUMPHREY,
C. P. HUMPHREY.
